4 Sheets-Sheet 2

<img alt="A detailed technical cross-sectional diagram of a mechanical device, labeled FIG. 2. The diagram shows a complex assembly of pipes, valves, and structural components. Various parts are labeled with numbers such as 19, 20, 28, 43, 46, 56, 55, 47, 48, 49, 34, 36, 34, 36, 42, 29, 30, 11, 28, 24, 25, 12, 10, 5, 52, 53, 54, 55, 56, 57, 58, 59, 60, 61, 62, 63, 64, 65, 66, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, UNITED STATES PATENT OFFICE.

HALBERT K. HITCHCOCK, OF PITTSBURGH, PENNSYLVANIA.

APPARATUS FOR GRADING ABRASIVE AND APPLYING SAME TO CONTINUOUS GRINDING SYSTEMS.

Application filed November 3, 1924. Serial No. 747,582.

The invention relates to apparatus for surfacing sheets of material, such as glass, marble, and the like, by subjecting such material to a series of grinding operations with 5 the use of abrasives of successively finer and finer grades. The invention has to do particularly with the means for supplying the grinding machines with the abrasive, ordinarily sand, which is graded while in 10 suspension in a liquid, ordinarily water, and is supplied to the grinding machines mixed with such liquid.

One object of the invention is to provide a system having all of its parts in duplicate 15 and so arranged that both sets of parts will normally be in use, but so designed that in case either half, or any part thereof, of the abrasive supply system is shut down or incapacitated from any cause, the entire grinding 20 system can be supplied with abrasive from the remaining half of the abrasive supply system, the capacity of each half being sufficient for this purpose.

A further object is to provide a duplicate 25 system for supplying abrasive to two long series of grinding machines in which the machines of each series act in succession on the surface being ground, and which supply system insures uniformity in the mixture 30 of abrasive supplied to corresponding parts of the two series and is so arranged that each series of grinding machines is supplied with abrasive from both halves of the duplicate supply system.

A further object is to provide an abrasive 35 supply system whereby a long series of grinding machines is supplied from a central grader and in such manner that the supply of abrasive to the more remote machines is as 40 adequate and uniform as it is to the close-by machines, and which system is so arranged that the entire series of grinding machines can be kept in operation notwithstanding temporary clogging or stopping of individual conduits and distributing means between the central grader and the grinding machines.

A further object is to provide an abrasive 45 supply system whereby a long series of grinding machines acting in succession on the surface being ground can be successively supplied with abrasive of progressively increasing fineness, and in which each machine is supplied with only one and uniform grade 50 of abrasive, and which system is so arranged

that the entire series of grinding machines can be kept in operation notwithstanding stoppage of the abrasive supply from the central grader for a limited period.

Other objects and advantages of the invention will appear from the detailed description hereinafter following.

In the drawings the invention is shown as embodied in an apparatus for effecting a continuous or straight-away grinding operation in which the sheet of glass or other material whose surface is to be ground is carried progressively across a series of grinding machines which, in succession, are supplied with finer and finer grades of abrasive, and in which the abrasive is divided in suspension in a liquid into grades according to fineness, and in which all parts are in duplicate and so arranged that normally both series of grinding machines are supplied with abrasive from both halves of the grinding system, but in which either half of the abrasive supply system can be utilized to supply both series of grinding machines.

In the drawings Fig. 1 is a diagrammatic plan view of a sufficient portion of the system to illustrate all of its necessary elements; Fig. 2 is a diagrammatic longitudinal vertical sectional view taken substantially on the line 2-2, Fig. 1; Fig. 3 is a plan view of the means, lying substantially below the plane 3-3, Fig. 2, for returning the abrasive mixture discharged from the grinding machines to the grading system; Fig. 4 is a diagrammatic transverse vertical section taken substantially on the line 4-4, Fig. 2, except for the fresh sand supply reservoir which is in advance of said section plane; Fig. 5 is a vertical sectional view through one of the secondary graders; Fig. 6 is an enlarged view of the upper portion thereof and illustrating the means for blowing out the supply pipes in case of clogging; Fig. 7 is a plan view showing a modification of the connections between the sumps and the primary graders; and Fig. 8 is a detailed sectional view of one of the control valves illustrated in plan in Fig. 7.

The grinding machines illustrated are of the suspended type of grinding heads or runners and are illustrated in two parallel series designated respectively A¹, A², A³, A⁴, A⁵, A⁶, A⁷, A⁸, etc. and B¹, B², B³, B⁴, B⁵, B⁶, B⁷, B⁸, etc. An actual installation embodying this invention employs thirteen grind-

ing machines in each series, but manifestly the number can be more or less as desired or found necessary. C^a and C^b represent the main graders, and which, if desired may be the sole graders for the abrasive, one normally supplying the abrasive for the A series of grinding machines and the other the abrasive for the B series of grinding machines. Adjacent each contiguous two grinding machines is a distributing vessel, said distributing vessels also being in two series, those of one series being designated D¹, D², D³, D⁴, etc. and those of the other series being designated E¹, E², E³, E⁴, etc. The distributing vessels of the two series are arranged in alternate or staggered relation, as shown in the plan view, Fig. 1, for a purpose hereinafter stated. These distributing vessels serve as local reserve supplies for abrading mixtures and preferably are constructed to serve as secondary graders, and are so illustrated in the drawings.

Each of the main graders C^a and C^b is of a type to separate the abrasive into grades of different fineness while in suspension in water by an upward flow at a decreasing velocity of a mixture of the abrasive and water, according to a principle heretofore patented by me, and are of the same general construction as that illustrated in my Patent No. 1,056,415. Said grading vessels are of inverted cone shape for the major portion of their heights with a cylindrical portion and an overflow trough at the top. The mixture of water and abrasive is introduced through the apices of the cones, through pipes 1^a and 1^b, respectively, thus producing upward currents in said vessels, and which, due to the shape of the vessels, gradually decrease in velocity, thus causing the abrasive to come to a state of equilibrium in horizontal strata of different fineness, the coarsest material being at the bottom and successive layers upwardly being of finer and finer material. The mixture of water and abrasive is withdrawn from each vessel by a series of open-ended pipes extending down into the vessel with their ends terminating at different levels, so that each pipe will withdraw the particular grade existing at the level at which its open end terminates. To facilitate removal of the several withdrawal pipes from the graders C^a and C^b said pipes extend upwardly and over the tops of said vessels. The number of these withdrawal pipes for each grader is the same as the number of distributing vessels D¹, etc. and E¹, etc. supplied by each grader, specifically, thirteen in number in the actual installation referred to. These pipes are designated on the drawings by the reference characters F¹, F², F³, F⁴, etc. for the pipes leading from the grader C^a to distributing vessels D¹, D², D³, D⁴, etc., and G¹, G², G³, G⁴, etc. for the pipes leading from the grader

C^b to distributing vessels E¹, E², E³, E⁴, etc. In this way successive distributing vessels in each series are supplied with successively finer and finer grades of abrasive.

The glass or other material to be ground is laid on tables, marked 2^a and 2^b (Fig. 4) for the two series, which travel on parallel tracks 3^a and 3^b located respectively underneath the two series of grinding runners, and which will be moved mechanically, continuously and slowly forward so as to pass in succession underneath the successive grinding runners of their respective series. These tables will be coupled in train and closely, so that in effect the operation is that of grinding a continuously traveling sheet of glass, by successive operations of a number of grinders thereon, thus progressively reducing the surface of the glass and imparting a progressively finer and finer finish thereto.

As already stated, each of the distributing vessels preferably constitutes a secondary grader. As shown (Fig. 5) each of said vessels is of inverted cone shape for the major portion of its height, surmounted by a cylindrical portion. The mixture of water and abrasive coming from a main grader enters through the top, as at 5, and the upward current which exists in each of such vessels causes grading of the abrasive, in suspension in the water, into strata of varying fineness, the coarsest being at the bottom and successively finer grades toward the top. Dipping into each such vessel are a number of open-ended pipes terminating at different levels therein so as to withdraw from said cone abrasive of different fineness. As illustrated, each secondary grader is provided with four withdrawal pipes, two long ones and two short ones, the former of which withdraw a relatively coarse grade while the latter withdraw a relatively fine grade. One of the long pipes, for instance that marked 6^a, leads to the grinding machine of the series belonging to the secondary grader under consideration, say the grader D¹, which is on the side of said grader toward the end from which the glass to be ground is coming in, say to the grinding table A¹, while the other long pipe, marked 6^b, leads to the corresponding grinding machine of the other series, say to the grinding machine B¹. One of the short pipes, that marked 7^a, leads to the next succeeding grinding machine of the series adjacent the secondary grader under consideration, say to the grinding machine A², while the other short pipe, marked 7^b, leads to the corresponding grinding machine of the other series of grinding machines, say to the machine B². This same arrangement is followed for each of the secondary grading vessels, so that each secondary grader supplies abrasive to four grinding machines, while each grinding machine is

supplied with abrasive from two secondary graders. Thus, the grinding table A¹ is supplied with the finer grade of abrasive from secondary grader E¹ and with the 5 coarser grade of abrasive from secondary grader D¹. Since, however, the fine grade from E¹ varies only very slightly from the coarse grade from D¹, table A¹ is supplied with abrasive of substantially the same degree of fineness.

The arrangement described holds true for each of the secondary graders, it being understood, of course, that the secondary graders in succession throughout each series 10 are supplied from the main graders with successively finer and finer grades of abrasive, as a result of which each table, notwithstanding that it receives abrasive from two secondary graders, is supplied with 15 abrasive of substantially the same grade, and the successive grinding machines throughout each series are supplied with abrasive of successively finer grades. The secondary graders are of such capacity as 20 to serve as reserve storage reservoirs for the abrasive, so that the grinders can be kept in continuous operation even though the supply from the main graders be entirely discontinued for a limited time. Also, by 25 supplying each grinding machine with abrasive from two secondary graders, it can be kept in continuous operation even though one of said graders should for some reason be shut down; and by cross connecting each 30 series of secondary graders to the opposite series of grinding machines all of the grinding machines can be kept in operation even though one entire series of secondary graders be shut down. Also, because of this 35 cross connection from each series of secondary graders to the opposite series of grinding machines, part of the abrasive coming from each of the main graders passes over to the machines supplied from the other primary 40 grader. In this way an intermingling and better blending of the abrasive is secured, thus insuring substantial uniformity of the 45 grades of abrasive supplied to the two series of grinding machines, with a resultant uniformity of finish of the glass by the two 50 series of grinding machines.

The mixture of water and abrasive thrown off by the grinding machines is gathered in splash troughs arranged at 55 both sides of both series of grinding machines, the troughs for the series A machines being marked 8^a and those for the series B machines being marked 8^b. These troughs are in sections with oppositely sloping bottoms for approximately each four grinding machines, as shown in Fig. 2, and from the 60 lowest points in their bottoms drains 9^a and 9^b, respectively, conduct the drainage to return troughs 10^a and 10^b, respectively, leading to the sumps 11^a and 11^b, from which

the drainage is returned to the main graders as hereinafter described. Fig. 3 shows two return troughs 10^a and two return troughs 10^b, but this is merely a mechanical convenience in order to have a sufficient slope to said return troughs. A single return trough for each series of machines will suffice.

Each of the secondary graders is provided with an overflow pipe 12 for carrying off 75 the excess water and fine abrasive. These pipes branch (Fig. 4) and connect to longitudinal pipes 12 extending above the splash troughs, and from which branches 12^a extend down into the splash troughs at the 80 points where their bottoms are highest and have their ends turned in opposite directions, as shown in Fig. 2, so that the surplus water overflowing from the secondary graders serves to wash out the splash 85 troughs.

Each secondary grader is also provided in its apex with an outlet 13 which drains to a splash trough, and which outlets are closed by means of rubber or other valves 14 carried on the lower ends of vertically movable pipes 15 which supply water to the secondary graders in order to produce upward currents therein, replace the water lost through the overflows from the system, and dislodge 90 and wash out any coarse sand which may pack in the apices of said vessels. To this end each of said pipes 15 is provided at its lower end with a hole 16 and has its upper end connected by cross pipe 17 to a longitudinal pipe 18 common to the two series of secondary graders and which receives water from a tank 19 supplied with fresh water through pipe 20 and provided with a float 21 and valve 22 for maintaining a constant 100 level of water therein. The overflow water and also the drain water and abrasive coming from the secondary graders and entering the splash troughs returns to the sumps through the troughs hereinafter referred to. 110

The return troughs 10^a and 10^b from the two series of grinding tables discharge respectively into the sumps 11^a and 11^b. Provision, however, is made to divert the water from either of said troughs to the opposite 115 sump. This is effected by bringing said troughs side-by-side (Fig. 3) and affording connection between the same by means of a dividing gate 24 and providing the return troughs with stop gates or valves 25^a and 25^b, respectively. Hence by opening gate 24 and closing one of the stop gates 25^a or 25^b all of the return water can be diverted to one or the other of the sumps. The return water enters the sumps through revolving screens 26^a, 26^b, for catching any dirt, fragments of glass, and the like, which screens are rotated from motors 27^a, 27^b, and discharge to dirt pans or bins 28^a, 28^b.

Each sump is divided into three com- 120 125 130

partments, by means of partitions 28, 29 and 30. These partitions are of the suspended type, that is, do not extend entirely to the bottoms of the sumps. Partitions 28 and 29 extend above the water level while partition 30 terminates a little below the water level. The return water enters in the compartment defined by partitions 28 and 29 and is compelled to travel to the bottom 10 of the sump and underneath the partitions in order to enter the other compartments in which it flows upwardly. The water and suspended abrasive in the other two compartments can flow from one to the other 15 over the top of partition 30.

Extending down into the compartment defined by the partitions 29 and 30 of each of the sumps are a pair of withdrawal pipes, those for the sump 11^a being designated 31^a and 32^a and those for the sump 11^b being designated 31^b and 32^b. These withdrawal pipes are connected through pumps to the two primary graders and in a way so that the mixture withdrawn from either sump 25 can be discharged into either grader, or both graders can be supplied from the same sump. Various arrangements of connections can be made to serve these purposes. In the arrangement shown in Figs. 2, 3 and 4 30 the withdrawal pipe 31^a is connected to pump 34, the withdrawal pipe 31^b is connected to pump 35; the withdrawal pipe 32^a is connected to pump 36 and the withdrawal pipe 32^b is connected to pump 37. The outlet pipes 34^a and 35^a (Fig. 4) from the pumps 34 and 35, respectively, lead to the pipe 1^a entering the apex of the grader C^a, and the outlet pipes 36^a and 37^a from the pumps 36 and 37, respectively, lead to the 40 pipe 1^b, entering the apex of the grader C^b. By this arrangement either grader can be supplied with abrasive mixture from either sump, or both graders can be supplied from either one or the other sump alone.

Normally only one of the pair of pumps 34 or 35 and one of the pair of pumps 36 and 37 will be used, the other two being reserve pumps. To provide for the contingency of both pumps of either of the above 50 named pairs becoming inoperative, and still be able to supply both graders with abrasive mixture, there is provided a diagonal connecting pipe 40^a leading from pump 36 or 37 to the inlet of grader C^a and another diagonal pipe 40^b leading from pump 34 or 35 to grader C^b. This cross-connection enables the use of both pumps of either pair, one discharging to one of the primary graders and the other discharging to the 55 other primary grader.

Fig. 7 illustrates an arrangement alternative to that shown in Fig. 3 for achieving the same purpose. As here shown the pipes 31^a and 31^b are connected to the casing of a 60 valve 33^a to which valve casing are also con-

nected the two pumps 34 and 35, while the pipes 32^a and 32^b are connected to the casing of a valve 33^b to which are also connected the two pumps 36 and 37. The valves 33^a and 33^b are of the construction shown in Fig. 8, with the rotary valve body provided with a cavity 38 arranged to connect adjacent sump and pump pipes, as for instance, in the case of valve 33^a, connect, in one position of the valve body, sump pipe 75 31^a to pump 34, and in the opposite position connect sump pipe 31^b to pump 35, and with a diametric passage 39 arranged in one position to connect sump pipe 31^a to pump 35, and in the opposite position to connect sump 80 pipe 31^b to pump 34. Valve 33^b can make exactly similar connections between sump pipes 32^a and 32^b and pumps 36 and 37. This arrangement enables any two of the available pumps to be used to withdraw material from both sumps or from a single sump and to discharge it to both of the primary graders.

Normally it is intended that the return water and abrasive coming from the series 90 A grinding machines will enter the sump 11^a and be returned to grader C^a, and that coming from the series B grinding machines will enter sump 11^b and be returned to grader C^b. The interchange of water and abrasive between the two sides taking place through the cross-connections from each of the secondary graders to a grinding machine on the opposite side, as hereinbefore explained. The cross connections between the 100 return troughs 10^a and 10^b and the various cross connections between the several pumps, as heretofore described, are not intended to effect interchange of water and abrasive between the two systems, but are emergency 105 connections to be used in case one of the sumps clogs or becomes incapacitated from any reason, or in case both pumps of either pair becomes incapacitated.

The pipes 34^a, 35^a, 36^a and 37^a, as well as the diagonal pipes 40^a and 40^b leading from the pumps to the primary graders are each provided with three-way cocks 47 by means of which the direct flow through said pipes can be interrupted and the stream diverted through branches 48 connecting with return pipe 49 leading to the sumps. This by-pass connection will be used to prevent clogging of the system when it becomes necessary to start up a new pump. For instance, in case 110 pump 34 is in operation and it becomes necessary to shut it down and start pump 35, the three-way cock 47 in the discharge pipe from pump 35 will be set to connect with return pipe 49, so that the mixture drawn by pump 35 from the sump will be returned to it. This connection will be maintained until pump 35 has gotten up to full speed, and then the three-way cock 47 in this discharge pipe will be turned to position to 115 120 125 130

discharge the mixture into the grading cone. Then the pump 34 can be stopped, and its three-way cock turned to close connection to the grader, without danger of the sand settling and clogging the system.

Each sump is provided with a normal overflow 41 and with a lower overflow 42, both leading to a sewer, the latter to be used in case it is necessary to lower the level of the water in the sump, for making repairs to the withdrawal pipes to the pumps, or for other reasons. The primary graders are also provided with overflows, viz., overflow troughs 43 from which pipes 43^a lead to a sewer.

For mechanical reasons, the sumps are formed of rectangular outline but with sloping bottoms, as a result of which there are angles at 44 in the bottom of each sump (Fig. 20 3). As the heavier sand may lodge or bank at these angles, means are provided for washing the same out, said means comprising a pair of pipes 45 extending down into the sumps and opening adjacent to these angles, 25 and which wash-out pipes are connected through pipes 46 and branches 46^a and 46^b to the upper parts of the main graders, said branches being provided with valves whereby when necessary or desired water can be admitted through the wash-out pipes.

Fresh abrasive, such as green sand, is supplied to the two systems from a storage bin or bins 50 which discharge into troughs 61^a and 61^b which in turn discharge into 35 the return troughs from the grinding machines in advance of the dividing and stop gates heretofore described, to-wit, at the points 52^a and 52^b, respectively (Fig. 3). The supply of fresh abrasive from the bins 40 to the troughs 51^a and 51^b is controlled by an automatic feeder, generally illustrated at 53 (Fig. 4) and which in turn is controlled by the density of the mixture in the main graders. This automatic control, in the 45 actual installation referred to, is of the type illustrated and described in my application Serial No. 687,702, filed January 22, 1924. Since any feeding device which is automatically controlled by the density of the 50 mixture in the system will answer the purpose, such device is only indicated and will not be further described.

In event that the systems become charged with surplus abrasive, the coarsest can be 55 withdrawn, preferably from the main graders C^a and C^b, such as by means of valve controlled outlets 55^a and 55^b near the apices of said graders and connected to pipe 56 leading to a storage bin comprising one compartment 57 for the coarser abrasive and a second compartment 58 for the finer abrasive 60 which will enter the said second compartment by overflow over the partition 59. Each of these bin compartments is supplied with 65 a valve controlled outlet connected to pipes

60 and 61, respectively, which lead to the return troughs 10^a and 10^b. A pipe 62 takes care of the overflow from this bin and also leads to the return troughs.

The fresh water line 20 which supplies 70 the tank 19 is extended along the two series of grinding machines, as at 64, and at suitable intervals is provided with flexible branches 65 to each of which is connected a nozzle 66 which is constructed to be 75 snapped over the open end of a pipe coming from a main grader and where it enters the secondary grader, in order to blow out any obstruction in such supply pipes due to the clogging of the mixture of water and abrasive therein. To enable this to be effected the supply pipes to the secondary graders extend through the tops of feed hoppers 67 at the tops of said secondary graders and terminate immediately inside said tops, and 80 said hoppers are open on one side, as at 68, to enable the nozzles 66 to be inserted and snapped onto the ends of such pipes (Figs. 6).

One reason for using a single distributing 90 vessel or secondary grader for each two grinding machines is to enable the supply pipes for said distributing vessels to be larger than would be the case if there were as many distributing vessels as grinding machines, 95 and thus reduce the liability of such pipes clogging. The snap-on nozzle arrangement described is an emergency device to be used in case nevertheless such supply pipes become clogged. Another reason for having a 100 single distributing vessel or secondary grader for each two grinding machines is that it reduces the number of withdrawal pipes from 105 each of the primary graders to one-half the number of grinding machines of each series, resulting in less pipe obstruction in the primary graders and thus insuring a better and more uniform grading of the material and a less clogging or banking of abrasive 110 therein.

In the operation of the system the surplus water and the mud, that is, the abrasive which has been pulverized to practical destruction, are eliminated in part by the overflow pipes 41 from the sumps and in part 115 by the overflow from the main graders, by way of the overflow troughs 43 and discharge pipes 43^a leading therefrom. The necessary amount of fresh water to supply the water lost through these overflows is supplied from 120 tank 19 and is introduced into the secondary graders, through the vertical pipes 15 there-in, and serves both to produce the upward grading currents in said secondary graders, and also to wash out any accumulation or 125 banking of coarse sand in the bottoms of said graders, through the drain orifices 13 there-in. The overflows from the secondary graders, and also the drainage mixture therefrom, as well as the overflow from the excess 130

sand bins 57, 58, returns to the system by being discharged into the return troughs leading from the grinding machines to the sumps. The required amount of fresh abrasive to replace that which has been worn out comes from the storage bin 50 and is introduced into the system in the required amount through the feeding device referred to which is controlled by the density of the mixture 10 in the system.

The systems illustrated and described has numerous important advantages. By having all of the parts of the system in duplicate throughout, and so arranged that each 15 set of grinding machines can be supplied from both halves of the abrasive grading and supply system, and by giving sufficient capacity to the abrasive grading and supply system, it is possible to have all of the parts 20 in normal use all of the time, and also possible to keep all of the grinding machines in operation in the event the whole or any part of one-half of the abrasive grading and supply system becomes incapacitated for any 25 cause. It is therefore possible to make the necessary adjustments, repairs and replacements, or cure any temporary incapacity in a part of the abrasive grading and supply system, without putting any of the grinding 30 machines out of operation or interfering in any way with their efficient operation, and is therefore possible to maintain the entire system in proper adjusted and operative condition, each half of the abrasive grading and 35 supply system standing ready to handle the entire supply of graded abrasive and supply it to all of the grinding machines.

Irrespective of the duplicate arrangement of the system, each half by itself provides an 40 efficient and advantageous arrangement in supplying abrasive to and keeping in constant operation a long series of grinding machines acting successively on the surface to be smoothed and progressively producing 45 a finer and finer surface thereon. By providing such long series of grinding machines with an abrasive supply system including a plurality of distributing vessels or secondary graders supplied from a central 50 primary grader, and each of which distributing vessels or secondary graders supplies one or more adjacent grinding machines, there is provided a reserve supply of abrasive and water adjacent the points of use thereof, as 55 a result of which the supply of abrasive to the remote machines is as adequate and uniform as it is to the near-by machines, a uniformity in the mixture is insured which would not otherwise be obtainable, and all 60 of said machines can be kept in operation even though certain of said distributing vessels or secondary graders should be incapacitated and in need of repair, and even though the supply of the mixture to said distributing 65 vessels or secondary graders should be

shut off for limited periods due to the clogging of supply pipes, leaks, necessary repairs to the pipes, or even interruptions in the operation of the central grader itself.

Ample provisions are made for keeping 70 clean and in proper operative condition all of the pipes, troughs, and sumps, for eliminating from the system the surplus water, mud, and worn out abrasive, for supplying the system with sufficient water and new 75 abrasive to maintain approximately constant the mixture in the system, for supplying each table with a substantially single and uniform grade of abrasive, and for supplying the successive grinding machines of 80 the series with progressively finer grades of abrasive, and producing such an interchange of the abrasive mixture between the two halves of the system as to insure substantial like conditions in corresponding parts in 85 the two halves.

I claim:

1. In apparatus for surfacing glass and the like, the combination of two grinding systems each comprising a series of grinding machines adapted to progressively and successively surface the material being ground, separate abrasive supply systems associated with the respective grinding systems and each comprising a plurality of liquid-suspension distributing and storage vessels, separate constantly operative means with each system to supply each of said vessels with graded abrasive, and connections for supplying each grinding machine 95 with abrasive from a distributing vessel of its own series and from a distributing vessel of the other series.

2. In apparatus for surfacing glass and the like, the combination of two grinding 105 systems each comprising a series of grinding machines adapted to reduce progressively and in succession the surface being treated; mechanism for continuously moving the material to be surfaced to and through said grinding machines in the respective series in succession, separate abrasive supply systems associated with each grinding system and each comprising a series of liquid-suspension abrasive distributing and storage vessels adapted to supply abrasive to adjacent grinding machines, and connections operable to supply each grinding machine with abrasive from a distributing vessel of its own series and from a distributing 115 vessel of the other series simultaneously.

3. Apparatus for surfacing glass and the like, comprising a plurality of separate grinding systems each system comprising a 125 series of grinding machines adapted progressively in succession to reduce the surface of material being ground, mechanism for continuously moving the material being ground through each series of grinding ma- 130

- chines, separate abrasive supply systems associated respectively with each series of grinding machines and each comprising a primary grader, a plurality of storage and distributing vessels adapted to hold the graded abrasive in liquid suspension adjacent the grinding machines and each connected to the primary grader of its systems by a selective conduit whereby abrasive of different fineness is supplied to successive distributing vessels, and separate conduits from distributing vessels of the different abrasive supply systems whereby each grinding machine of each series is supplied with abrasive from distributing vessels of more than one abrasive supply system.
4. In apparatus for surfacing glass and the like by a continuous series of grinding operations, the combination of two grinding systems each comprising a plurality of constantly operative grinding machines, mechanism for continuously moving the material to be surfaced to the grinding machines of each series in succession, separate abrasive supply systems associated with each grinding system and each comprising a primary constantly operative grader and a plurality of distributing and storage vessels adjacent the grinders and constantly supplied from the primary grader with graded abrasive, and a plurality of withdrawal pipes from each distributing vessel leading to a grinding machine of its own system and to a grinding machine of the other system.
5. In apparatus for surfacing glass and the like, the combination of two grinding systems each comprising a plurality of grinding machines acting in succession on the material to be surfaced, an abrasive supply system associated with each grinding system and each comprising a plurality of grading vessels supplied in succession with finer and finer grades of abrasive, withdrawal pipes from each of said grading vessels arranged to separately withdraw a fine grade and a coarse grade, and connections for conducting one of said grades to a grinding machine of its own series and the other grade to a grinding machine of the other series.
6. In apparatus for surfacing glass and the like, the combination of two grinding systems each comprising a plurality of grinding machines acting in succession on the material to be surfaced, an abrasive supply system associated with each grinding system and each comprising a primary grader and a plurality of secondary graders supplied in succession from the primary grader with finer and finer grades of abrasive, withdrawal pipes from each of said grading vessels arranged to separately withdraw a fine grade and a coarse grade, and connections for conducting one of said grades to a grinding machine of its own series and the other grade to a grinding machine of the other series.
7. In apparatus for surfacing glass and the like, the combination of two grinding systems each comprising a plurality of grinding machines acting in succession on the material to be surfaced, an abrasive supply system associated with each grinding system and each comprising a plurality of grading vessels supplied in succession with finer and finer grades of abrasive, withdrawal pipes from each of said grading vessels arranged to separately withdraw a fine grade and a coarse grade, and connections for conducting a part of the coarse and a part of the fine grade to two successive grinding machines of its own series and another part of the coarse and another part of the fine grade to two successive grinding machines of the other series.
8. In apparatus for surfacing glass and the like, the combination of two grinding systems each comprising a plurality of grinding machines acting in succession on the material to be surfaced, an abrasive supply system associated with each grinding system and each comprising a primary grader and a plurality of grading vessels supplied from the primary grader in succession with finer and finer grades of abrasive, withdrawal pipes from each of said grading vessels arranged to separately withdraw a fine grade and a coarse grade, and connections for conducting a part of the coarse and a part of the fine grade to two successive grinding machines of its own series and another part of the coarse and another part of the fine grade to two successive grinding machines of the other series.
9. In apparatus for surfacing glass and the like, the combination of two grinding systems, each comprising a series of grinding tables adapted progressively and successively to reduce the surface of material being treated and mechanism for continuously moving the material through each series of grinding machines, a separate constantly operative abrasive grading system associated with each grinding system and comprising a sump, return conduits arranged to return the discharge from said grinding systems separately to the two sumps or collectively to either sump, a pair of withdrawal pipes for each sump, a pump for each of said withdrawal pipes, and piping and valve arrangements whereby the abrasive mixture can be returned simultaneously and separately from either sump to either grading system, or from a single sump to both grading systems.
10. In apparatus for surfacing glass and the like, the combination of two grinding systems, each comprising a series of grinding tables adapted progressively and successively to reduce the surface of material

being treated and mechanism for continuously moving the material through each series of grinding machines, an abrasive grading system associated with each grinding system, means for returning the discharge from each of said grinding systems to its own grading system, and connections between said grading systems whereby abrasive material passes from each thereof to the other thereof.

11. In apparatus for surfacing glass and the like, the combination of two grinding systems, each comprising a series of grinding tables adapted progressively and successively to reduce the surface of material being treated and mechanism for continuously moving the material through each series of grinding machines, an abrasive grading system associated with each grinding system comprising a series of liquid-suspension storage and distributing vessels adjacent the grinding machines, means for returning the discharge from each of said grinding systems to its own grading system, connections between said grading systems whereby abrasive material passes from each thereof to the other thereof, and means for separately supplying to each primary grader of said grading systems sufficient new abrasive to maintain approximately constant the quantity of abrasive therein.

12. In apparatus for surfacing glass and the like, the combination of two grinding systems, each comprising a series of grinding tables adapted progressively and successively to reduce the surface of material being treated and mechanism for continuously moving the material through each series of grinding machines, an abrasive grading system associated with each grinding system, duplicate sumps, two conduits, one normally returning the discharge from one grinding system to one sump and the other returning the discharge from the other grinding system to the other sump, means for returning the abrasive mixture from each sump to the grading system from which it receives the discharge, connections between said grading systems whereby abrasive material passes from each thereof to the other thereof, and means for independently supplying to each of said return conduits sufficient new abrasive to maintain approximately constant the quantity of abrasive in each grader.

13. In apparatus for surfacing glass and the like, by a series of continuous operations, the combination of a series of grinding runners arranged to act in succession on a sheet to be surfaced, grading apparatus comprising a primary grader and a series of secondary graders for dividing an abrasive in suspension in a liquid into various grades ranging from coarse to fine, means for conducting progressively finer grades of abrasive to successive grinding runners, whereby

the successive runners produce a progressively finer and finer surface on the sheet, and means for supplying sufficient new abrasive to maintain approximately constant the various grades in the primary grader.

14. In apparatus for surfacing glass and the like, the combination of a series of grinding runners, means for continuously conveying the sheets to be surfaced to said grinding runners in succession, a series of grading vessels located at intervals adjacent said series of grinding runners, different ones of said grading vessels being supplied with different grades of abrasive, said vessels being arranged to divide said abrasive in suspension in liquid into coarse and fine grades, and means for separately conducting the various grades of abrasive from each of said grading vessels to a plurality of runners.

15. In apparatus for surfacing glass and the like, the combination of a series of grinding runners, means for continuously conveying the sheets to be surfaced to said grinding runners in succession, a series of grading vessels located at intervals adjacent said series of grinding runners, different ones of said grading vessels being supplied with different grades of abrasive, said vessels being arranged to divide said abrasive in suspension in liquid into coarse and fine grades, and means for supplying each grinding runner with a separate grade of abrasive from a plurality of said grading vessels.

16. In apparatus for surfacing glass and the like, the combination of a series of grinding runners, means for continuously conveying the sheets to be surfaced to said grinding runners in succession, apparatus for dividing an abrasive in suspension in liquid into various grades ranging from coarse to fine, a series of grading vessels located at intervals adjacent said series of grinding runners and arranged to divide the abrasive in suspension in liquid into coarse and fine grades, means for conducting different grades of abrasive to different ones of said grading vessels, and means for separately conducting the various grades of abrasive from each of said grading vessels to a plurality of runners.

17. In apparatus for surfacing glass and the like, the combination of a series of grinding runners, means for continuously conveying the sheets to be surfaced to said grinding runners in succession, apparatus for dividing abrasive in suspension in liquid into various grades ranging from coarse to fine, a series of grading vessels located at intervals adjacent said series of grinding runners and arranged to divide the abrasive in suspension in liquid into coarse and fine grades, means for conducting different grades of abrasive to different ones of said grading vessels, and means for supplying each grinding runner with a separate grade

of abrasive from a plurality of said grading vessels.

18. In apparatus for surfacing glass and the like, the combination of a series of grinding runners arranged to act in succession on a sheet to be surfaced, a series of grading vessels located at intervals adjacent said series of grinding runners and supplied in succession with finer and finer grades of abrasive and arranged to divide said abrasive in suspension in liquid into coarse and fine grades, and means for separately withdrawing the several grades from each grading vessel and conducting the coarse grade to one of said grinding runners and the fine grade to a succeeding grinding runner of the series. 70

19. In apparatus for surfacing glass and the like, the combination of a series of grinding runners arranged to act in succession on a sheet to be surfaced, a series of grading vessels located at intervals adjacent said series of grinding runners and supplied in succession with finer and finer grades of abrasive and arranged to divide said abrasive in suspension in liquid into coarse and fine grades, and means for separately withdrawing the various grades from each grading vessel and conducting to each grading runner the fine grade from a preceding grading vessel and the coarse grade from a succeeding grading vessel, whereby the sheet is given a progressively finer and finer surface by successive grinding runners. 85

20. In apparatus for surfacing glass and the like, the combination of a series of grinding runners arranged to act in succession on a sheet to be surfaced, grading apparatus for dividing an abrasive in suspension in a liquid into various grades ranging from coarse to fine, a series of liquid-suspension abrasive distributing vessels located at intervals adjacent said series of grinding runners, means for simultaneously conducting a definite and different grade of abrasive from said grading apparatus to each of said distributing vessels, and means for simultaneously conducting the abrasive from each of said distributing vessels to a plurality of runners acting on different sections of glass. 100

21. In apparatus for surfacing glass and the like, the combination of a series of grinding runners arranged to act in succession on the sheet to be surfaced, grading apparatus for dividing an abrasive in suspension in a liquid into various grades ranging from coarse to fine, a series of secondary graders located at intervals adjacent said series of grinding runners, means for conducting a definite and different grade of abrasive to each of said secondary graders, said secondary graders being arranged to separate the abrasive supplied thereto in suspension in a liquid into coarse and fine grades, and means 115

for separately withdrawing the grades from each of said secondary graders and conducting the coarse grade to one of said grinding runners and the fine grade to a succeeding grinder runner of the series. 120

22. In apparatus for surfacing glass and the like, the combination of a series of grinding runners arranged to act in succession on a sheet to be surfaced, grading apparatus for dividing an abrasive in suspension in a liquid into various grades ranging from coarse to fine, a series of secondary graders located at intervals adjacent said series of grinding runners, means for conducting progressively finer grades of abrasive to each of said secondary graders in succession, said secondary graders being arranged to divide the abrasive supplied thereto in suspension in the liquid into coarse and fine grades, and means for supplying each grinding runner with the fine grade from a preceding secondary grader and the coarse grade from a succeeding secondary grader, whereby the sheet to be ground is given a progressively finer and finer surface by said grinding runners. 125

23. In apparatus for surfacing glass and the like, the combination of a series of grinding runners, means for continuously moving a sheet to be surfaced to said grinding runners in succession, grading apparatus for dividing an abrasive in suspension in a liquid into various grades, a series of secondary grading vessels located at intervals adjacent said series of grinding runners, means for separately conducting the various grades to different ones of said secondary grading vessels, means for separately withdrawing the grades from the secondary grading vessels and conducting the same to different ones of said grinding runners, means for returning the drainage from said grinding runners to the grading apparatus, means to eliminate the worn out abrasive from the system, and automatic means for supplying sufficient new abrasive to maintain approximately constant the quantity of abrasive in the primary grader. 130

24. In apparatus for surfacing glass and the like, the combination of a series of grinding runners, means for continuously moving a sheet to be surfaced to said grinding runners in succession, grading apparatus for dividing an abrasive in suspension in a liquid into various grades, a series of secondary grading vessels located at intervals adjacent said series of grinding runners, means for separately conducting the various grades to different ones of said secondary grading vessels, means for separately withdrawing the grades from the secondary grading vessels and conducting the same to different ones of said grinding runners, means for returning the drainage from said grinding runners to the grading apparatus, 135

means to eliminate the worn out abrasive from the system, and means controlled by the density of the mixture in the primary grading apparatus for supplying sufficient new abrasive to maintain approximately constant the quantity of abrasive in the primary grader.

25. In apparatus for surfacing glass and the like, the combination of grinding mechanism, grading apparatus for dividing an abrasive in suspension in a liquid into various grades, means for separately conducting the grades to said grinding mechanism, a sump, means to return the drainage from said grinding mechanism to said sump and from said sump to said grading apparatus, means to withdraw abrasive from the grading apparatus, and a bin receiving said abrasive and discharging to the sump.

26. In apparatus for surfacing glass and the like, the combination of grinding mechanism, grading apparatus for dividing an abrasive in suspension in a liquid into various grades, means for separately conducting the grades to said grinding mechanism, a sump, means to return the drainage from

said grinding mechanism to said sump and from said sump to said grading apparatus, means to withdraw abrasive from the grading apparatus, bins receiving said abrasive and arranged to separate the same into coarse and fine grades, and means for separately discharging said grades from said bins to said sump.

27. In apparatus for surfacing glass and the like by a series of continuous operations, the combination of a series of grinding runners arranged to act in succession on a sheet to be surfaced, a grading apparatus for dividing an abrasive in suspension in a liquid into various grades ranging from coarse to fine, means for conducting progressively finer grades of abrasive to successive grinding runners, whereby the successive runners produce a progressively finer and finer surface on the sheet, and means for supplying sufficient new abrasive to maintain approximately constant the various grades in the grader.

In testimony whereof, I sign my name.

HALBERT K. HITCHCOCK.
